CLAIM

The ornamental design for slippers with bow tie as shown and described.

DESCRIPTION

FIG. 1 is a perspective view of a slipper with bow tie of my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The left slipper with bow tie is a mirror image of the right slipper with bow tie shown in FIGS. 1-7 and is not shown but also claimed.

The broken lines depict portions of the slipper with bow tie that form no part of the claimed design.
